APPARATUS FOR PLACEMENT OF CONCRETE

Robert William Baily, Narberth, Pa.

Application April 13, 1936, Serial No. 74,114

4 Claims. (Cl. 94—48)

My present invention has for one of its objects the provision of an apparatus of simple and inexpensive construction for practicing a method of placement of concrete, which method is disclosed in my co-pending application Serial Number 698,471, filed November 17, 1933, the present application being a continuation in part thereof.

A further object is to provide an apparatus for use with a grid-like member adapted to reinforce concrete floors, slabs or the like, the apparatus being effective to compact concrete into the grid-like member, even into spaces below bottom surfaces of the member so that all voids or air pockets are eliminated and the concrete contacts with the entire surface of the grid-like member exposed to the concrete so that no air or water can get to the metal, thus causing deterioration.

Still a further object is to provide apparatus for vibrating concrete so that it will settle into the interstices of a metal grid-like reinforcing member even though the member itself is quite rigidly mounted, and therefore only semi-susceptible or altogether non-susceptible to vibration.

A further object is to provide an apparatus for imparting vibrations to the upper surface of plastic concrete in grid-like reinforcing members without imparting such vibrations to the grid-like members, whereby the concrete is compacted by the vibrations and rendered more plastic so as to fill all interstices in the grid-like members.

Still a further object is to provide an apparatus for use in connection with non-flowing, unworkable filler concrete deposited in metal grid-like reinforcing members, whereby such concrete may be compacted into the members by the application of vibrations thereto by the apparatus which renders the concrete flowable and workable so that it can be so compacted to eliminate voids and air pockets therein.

A further object is to provide apparatus which can also be used in the treatment of a material with or without reinforcement and with or without grid-like supporting structures therefor, to which end I provide one form of apparatus usable upon the upper surface of a material to be treated by propelling the apparatus across the material and allowing all or part of the weight of the apparatus to be imposed upon the material while the apparatus is vibrated.

Another object is to provide a form of my apparatus provided with downwardly extending fingers so that as the apparatus is positioned

in contact with the upper surface of the material to be treated, the fingers are immersed in the material, and since the fingers partake of the vibrations of the apparatus, they in turn transmit vibrations to the interior of the material while the apparatus vibrates the material from its upper surface, this apparatus being associable with the material so that the fingers are immersed without the apparatus resting on the surface of the material if it is desirable to treat the material interiorly by the fingers without imparting vibrations to the upper surface of the material.

My invention consists in the provision of apparatus in which the construction, arrangement and combination of the various parts will accomplish the objects contemplated, as herein-after more fully set forth, pointed out in my claims, and illustrated in the accompanying drawings, in which:

Figure 1 is a perspective view of a portion of a grid-like reinforcing member with which my apparatus is used.

Figure 2 is a perspective view of another form of grid-like reinforcing member.

Figure 3 is an enlarged sectional view on the line 3—3 of Figure 1, showing my apparatus in side elevation and being operated to accomplish the first step in the method disclosed in my above referred to co-pending application.

Figures 4 and 5 are similar side elevations showing additional steps in practicing the method.

Figure 6 is a sectional view on the line 6—6 of Figure 2, showing concrete in place after my method of placement has been practiced on the grid-like member of Figure 2.

Figure 7 is a front elevation of a modified form of apparatus.

Figure 8 is a diagrammatical end elevation of Figure 7.

Figure 9 is a front elevation of an apparatus similar to that shown in Figure 7 with an internal combustion engine being used as the motive power instead of an electric motor.

Figure 10 is an end elevation of Figure 9, parts being broken away and other parts being shown in section.

Figure 11 is a front elevation of another modified form of apparatus provided with fingers to extend into the concrete or other material to be treated.

Figure 12 is an end elevation of the same.

Figure 13 is a diagrammatical end elevation

showing a different manner of using the apparatus shown in Figures 11 and 12.

Figure 14 is a front elevation showing a different manner of mounting manipulating handles 5 on the apparatus; and

Figure 15 is an end elevation of same.

On the accompanying drawings I have used the reference numeral 10 to indicate a supporting beam such as used under concrete floor slabs 10 or the like either in buildings, bridges or other structures.

A grid member is indicated generally by the reference character A and comprises T irons 11 having notches 12 receiving bars 14. The bars 14 15 are arranged on edge as illustrated, and their ends may be bent as indicated at 15 to retain them in position.

Grid-like members of the form illustrated and 20 also other forms are built up of steel shapes into which is placed concrete to fill the interstices and to form the top wearing surface of a floor or slab. In some cases, the upper edges or 25 surfaces of the grid-like member A are allowed to remain at the top surface of the concrete to assist in resisting the wear of traffic, for instance, on 30 bridges and viaducts. In all cases, the concrete is relied upon to furnish the filler between the various elements of the grid-like member, to furnish or assist in furnishing the top wearing surface and to contribute a large proportion of the 35 strength of the slab against deflection from superimposed loads.

Obviously, to obtain the greatest total strength 35 from the combination of metal and concrete, it is essential that the concrete make intimate contact with all the surfaces of the metal grid-like member and that the concrete itself have the greatest possible density, not only to give the concrete the greatest possible inherent strength, 40 but also to prevent the ingress of water or other destructive agents against the surfaces of the metal to eliminate the possibility of corrosion.

In the construction of such slabs it has been 45 found to be exceedingly difficult to place the concrete in a manner that will exclude voids and air pockets in the mass and to bring the concrete into intimate contact with the metal, especially in concave corners of the metal and beneath cross bars thereof. Ramming the concrete by hand 50 or with impact hammers or the like, or manipulating its upper surface with frictional floats or trowels, does not satisfactorily accomplish the desired result. In most grid-like systems, vibrations applied to the grid do not accomplish the 55 desired effect since the grids are rigidly attached to heavy supports which do not allow the concrete to be vibrated and also the grid is too rigid and heavy for vibrations to be imparted to it so that it will vibrate the concrete, causing it to 60 settle into the interstices of the grid.

My method of placing concrete in the grid-like member involves simultaneous surface manipulation of the concrete and the application of vibration to the mass of concrete placed upon the 65 grid-like system without necessarily vibrating the grid itself, thus forcing the concrete down into the interstices of the grid, into all the corners thereof, into intimate contact with all surfaces thereof and beneath all cross bars, while 70 at the same time allowing the use of a dryer and harsher concrete and the use of larger coarse aggregate in the mixture. All of these factors produce the most nearly perfect combination 75 having the greatest combined strength and wear resistant qualities when the slab is completed.

In fact, my method will permit the satisfactory placement of concrete which would otherwise be non-flowing and unworkable.

My apparatus comprises a vibrator plate 16 having a vibrator mechanism B thereon and a handle 18 for manually manipulating the plate 16. The plate 16 preferably has a beveled or rounded leading edge 20. The vibrator mechanism B may consist of an electric motor 22 or other power unit, means for mounting the vibrator mechanism on the plate 16, such as by a casing 24 and an off-center weight 26 on the shaft of the motor. The casing 24, as illustrated, houses the off-center weight 26.

It will be obvious that rotation of the motor 15 shaft, causing rotation of the off-center weight 26 will impart vibration to the vibrator plate 16. The effective weight of the vibrator can be increased by supporting plate-like weights 28 thereon, the number of which can be varied. 20 These are preferably supported floatingly, for instance, by mounting them slidably on supporting rods 30 extending from the upper surface of the vibrator plate 16 and arranging springs 32 and 34 on the rods.

Thus the plates 28 are supported so that their weight is effective to increase the weight of the vibrator unit, yet the vibrator mechanism does not have to overcome the inertia of the plates 28 and move them up and down each revolution of 30 the motor shaft. Since the shaft rotates, there will also be horizontal vibration of the plate 16 as well as vertical and this is prevented from being transmitted to the weights 28 by the rods 30 bending as illustrated in an exaggerated manner in Figure 8.

The plates thus produce a continuous downward pressure but without absorbing any considerable proportion of the vibratory energy.

The weights 28 and 28a being in non-rigid 40 relation to the plate 16, which may be considered a base, continuously impose their weight as a gravity load upon the plate without substantial resistance to the vibration of the plate. The vibrator is preferably driven at a speed which is 45 out of resonance with the load, the speed being preferably high in order to effectively increase the flowability of the concrete.

In practicing the method for which my apparatus is designed concrete 36 is deposited in the 50 grid-like member A (see Figure 3) by shovels or from discharge chutes or the like. Enough is deposited in the grid-like member to fill it with some surplus for manipulation. The concrete is preferably somewhat dry for obtaining maximum 55 strength since sloppy concrete does not have the requisite strength even though it could be used and would eliminate the difficulty of having voids and air pockets, as indicated at 38 and 40 respectively, because it can flow into the interstices 60 without difficulty.

With respect to the illustration of the concrete, it is shown as sectioned with stippling to indicate the sand, gravel, crushed stone or other aggregate in the concrete so as not to confuse the 65 concrete with the air pockets 40.

After deposit of the concrete or while it is being deposited, the vibrator plate 16 is preferably propelled manually across the concrete in an inclined position, with the vibrator mechanism B in operation so as to drive the air out of the air pockets and voids and with the inclination tending to force the concrete down between the T irons 11 and the bars 14 as well as under the bars.

I have found it advisable to propel the vibrator plate 16 across the concrete to drive out the major portion of the air, as shown in Figure 3, then back it up and propel it across once more to drive out the remaining air, as shown in Figure 4.

There should be enough concrete so that during both of these operations the vibrator plate 16 does not come in contact with the grid-like member so that only the concrete is vibrated and there is no possibility of the vibrator tending to vibrate the grid-like member. By contact therewith, the apparatus will perform its function even if it rests directly upon the grid-like structure, for in this position it will cause the grid-like member to vibrate, such vibrations being transmitted to the concrete by the grid-like member to cause the concrete to flow to position filling all void spaces and eliminate any trapped air and surplus water. For instance, in Figure 5 the plate 16 is illustrated in contact with the grid-like member A and the vibrator B can be operated in this position to thus impart vibrations to the grid-like member.

After the steps of Figure 3 and Figure 4, the remaining concrete can be trowelled off by the vibrator plate 16 drawing it in a reverse direction, as indicated by the arrow in Figure 5, with the vibrator mechanism in operation. This last operation eliminates stripping off or trowelling by hand to obtain a smooth surface and the concrete is left in position untouched and undisturbed. Hand levelling would tend to tear and disturb the surface, but by my method, such injury is obviated.

In Figure 2, I have shown another form of grid-like member with which my apparatus may be used. It consists of supporting T irons 11a, flat bars 14a and a plate 17 supported by hook bolts 19. The plate 17 forms a bottom for the concrete to rest on, while in Figure 1, the horizontal flanges of the T irons 11 form such a bottom.

In Figure 6, I have shown how the concrete placed by my method fills the space between the bottom edges of the bars 14a and the bottom plates 17. Likewise, in the form of grid shown in Figure 1, the space between the bottom edges of the bars 14 and the horizontal flanges of the T irons 11 will be filled.

The apparatus shown in Figures 9, 10, 14 and 15 may or may not be provided with downwardly extending fingers 45. In these figures I have indicated the fingers with dotted lines.

In Figures 9 and 10 I have shown a modified form of apparatus provided with floating weight producing members 28 and 28a. The weight 28a may be removed at which time the mass of the weight 28 will be less than the weight of the plate 16. With the weight 28a in place, the total mass of the weights 28 and 28a will equal that of the plate 16. Additional weights 28a may be used so that the total mass of the weights will exceed that of the plate 16. Likewise the total mass of the weights may be so selected that it will be in resonance with the period of vibration of the plate 16 or out of resonance therewith as desired. It is obvious that the same objects may be obtained by various combinations of the weight 28 with one or more weights 28a.

In Figures 9 and 10 I have also illustrated the prime mover such as an internal combustion engine 41 carried on the weight 28a, although it could be otherwise supported as on the plate 16, as shown in Figure 7. The object of supporting

the prime mover on the weight 28a is to furnish a means for damping the transmission of vibrations from the plate 16 or the vibrator mechanism 24 to the prime mover 41. Power is transmitted from the prime mover to the vibrator mechanism by means of a flexible, and preferably elastic, belt 42 engaging a drive pulley 43 on the prime mover and a driven pulley 43a on a shaft 44 journaled in the vibrator housing 24. This shaft has the out-of-balance weight 26 secured to it.

In Figures 9 and 10 I have also shown the manipulating handles 18 connected to the weights 28 and 28a for the purpose of damping the transmission of vibrations from the vibrator 15 24 and the plate 16 to the handles.

If desired the downwardly extending fingers 45 may be secured to the lower surface of the plate 16, as shown in Figures 11, 12 and 13. These are attached to the plate by means of bolts 46, 20 so that when the vibrator mechanism 24, mounted on the plate, operates, the vibrations imparted to the plate will be communicated to the fingers 45 and from the fingers 45 to the material 36, causing the material to thereby be vibrated. 25 Likewise, the plate 16 being in contact with the upper surface 36a of the material will impart vibrations directly to the material. Since the out-of-balance weight 26 rotates, the vertical movements imparted thereby to the plate 16 30 will cause the plate to vibrate the material 36, while the horizontal vibrations imparted thereto will cause the fingers 46 to impart vibrations to the material, whereby the material has vibrations imparted to it both from above externally and 35 from the fingers internally.

In Figure 13 I have shown the bottom plate 16 out of contact with the surface of the material 36 and the lower ends of the fingers 45 as engaging a sub-grade 48. In some uses of the apparatus it may be advisable to have the fingers submerged in the concrete without the plate 16 being in contact therewith, and in other instances to further have the lower ends of the fingers contacting with the sub-grade as shown in Figure 13. 45 Figures 11, 12 and 13 have reference to the placing of concrete on a sub-grade, whereas the concrete can also be placed in the containing forms shown in Figures 1 and 2 and the lower ends of the fingers 45 engaging the form instead of the 50 sub-grade as shown in Figure 13.

In Figures 14 and 15 I show a modification wherein the handles 18 are attached to the plate 16 by flat, horizontal, flexible belts 51 attached by suitable brackets 52 to the plate 16. The handles 18 are attached to the belts 51 intermediate the brackets 52. Due to the action of the out-of-balance weight 26, the plate 16 will have lateral movements, but the belts 51 having lateral flexibility will damp out the vibrations before they reach the handles 16. Likewise the vibrations caused by up and down movement of the plate 16 will, because of the vertical flexibility of the belts 51, be damped before they reach the 60 handles 18. 65

Instead of a flat bottomed vibrator plate 16 as illustrated I may use other shapes of vibrating devices to compact the concrete, such as vibrating rollers or the like as shown in my Patent No. 1,876,271 and in the Baily and Gage Patent No. 70 2,025,703, or other appropriate devices.

The change just suggested in the apparatus and other modified forms of structure or mechanical equivalents might be used without departing from the real spirit and purpose of my invention and 75

the method of agitating the concrete by vibration can be performed with various apparatus I have not disclosed and still be reasonably included within the scope of my claims.

5 I claim as my invention:

1. Apparatus for compacting material which becomes plastic when vibrated, comprising a member having a substantially flat under surface adapted to rest on the top of and cover the material being treated and transmit vibrations thereto, a series of fingers secured to the under surface of the member and projecting downwardly therefrom a substantial distance, a weight made up of a series of separately removable parts, 10 yieldable means for supporting the weight on the member, and mechanism for imparting vibrations to the member, and through it to the fingers, whereby when the member rests on the material with the fingers immersed in the material, the material is subjected to surface vibration and to internal vibrations in directions some of which are horizontal for a substantial depth while under pressure.

2. Apparatus for compacting material which becomes plastic when vibrated, comprising an im- 25 perforate member having a substantially flat under surface adapted to rest on the top of the material and transmit vibrations thereto, a series of fingers secured to the under surface of the member and projecting downwardly therefrom a substantial distance, and mechanism for imparting vibrations to the member, and through it to the fingers, whereby when the member rests on the material with the fingers immersed in the material, the wholly covered material is subjected to surface vibration and to internal vibrations in directions some of which are horizontal for a substantial depth while under pressure, and a weight imposed upon but floatingly supported relative 30 to said member but out of resonance therewith, whereby continuous pressure is transmitted therethrough to the material thereby assisting in the compaction of the material.

3. Apparatus for compacting material which becomes plastic when vibrated, comprising a 35 member having a substantially flat under surface

adapted to rest on the top of the material and transmit vibrations thereto, a series of fingers secured to the under surface of the member and projecting downwardly therefrom a substantial distance, said member having substantial weight, mechanism for imparting vibrations to the member, and through it to the fingers, whereby when the member rests on the material with the fingers immersed in the material, the material is subjected to surface vibration and to internal vibrations in directions some of which are horizontal for a substantial depth while under pressure, a prime mover associated with said vibrator mechanism, flexible means for transmitting power from said prime mover to said mechanism, means for 40 damping the transmission of vibrations from the mechanism to the prime mover, said prime mover being of substantial weight, means for suspending the prime mover in resilient relation above the vibrator member whereby to impose continuously its weight as a supplemental gravity load upon the member without substantial resistance to the vibration of the member, and means for propelling said apparatus over and through the material to be vibrated.

4. A unitary mobile apparatus for compacting material which becomes plastic when vibrated having a flat faced member adapted to rest on and wholly cover a definite area of surface of such material and adapted to be moved about on such 45 surface during operation, vibrators extending downwardly from the underside of the member for a substantial distance, said vibrators being slender to permit free movement of the member over the surface of the material and being adapted to be moved with said member, a vibratory mechanism for imparting vibration to the member and to the vibrators, some of which vibrations are substantially horizontal, said mechanism being mounted to impose its weights on the 50 member so that portions of the material may be conveniently successively subjected to vibrations applied simultaneously to the material and to the surface of the material while such portions are covered and subjected to surface pressure.

ROBERT WILLIAM BAILY.
